UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed May 11, 1921. Serial No. 463,664.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms, whereby when the filling reaches a predetermined degree of exhaustion, the train of mechanism is set in operation to effect replenishment of filling.

Several types of feeler mechanisms have heretofore been devised, and among these is that which has now become generally known as the "side swipe feeler mechanism." The present invention is more especially directed to the side swipe type of feeler mechanisms, and includes a feeler arm or carrier which is normally supported to extend rearwardly in a direction inclined to the longitudinal axis of the shuttle or lay movement, and a feeler tip which is mounted for movement along the feeler arm or carrier in a direction longitudinally of the shuttle by the frontward pressure of the filling in the shuttle until substantial exhaustion thereof, and which, when filling is substantially exhausted on a detecting beat, fails to be moved along the feeler arm in a direction longitudinally of the shuttle, and means for effecting replenishment of filling when the feeler fails to be moved relative to the feeler carrier in a direction longitudinally of the shuttle.

The new feeler mechanism is illustrated in the accompanying drawings, wherein:

Fig. 1 is a perspective view of the feeler or detecting side of the loom, showing only sufficient portions of the loom to make clear the construction and mode of operation of the present invention;

Fig. 2 is a plan view showing more particularly the operation of the feeler mechanism when the shuttle contains a working supply of filling on a detecting beat;

Fig. 3 is a view similar to that of Fig. 2, showing the action of the feeler mechanism when the filling is substantially exhausted on a detecting beat;

Fig. 4 is a section on the broken line 4—4 of Fig. 2;

Fig. 5 is a detached detail showing one good form of sliding connection between the feeler tip and feeler arm and some of the associated parts.

The loom frame 1 has mounted thereon the brackets 2, one at each side of the loom for supporting the transverse or rock shaft 3 which is normally under the influence of a spring, not shown, for holding the parts in the position indicated in Fig. 1. Rising from the rock shaft 3 is the arm 4 to which is pivoted at 5 the actuator 6, the front end portion 7 of which is adapted to be engaged by an operating member 8 which may be conveniently formed as or part of the cam follower or weft hammer mechanism, as usual and well understood in this type of loom.

The lay 9 has the shuttle-box 10, the front wall of which is slotted at 11 as usual for the entrance of the feeler. The shuttle 12 has its front wall 13 slotted for the entrance of the feeler to feel for the filling 14 on the filling carrier 15 which is mounted in the shuttle. These parts may be as usual in this general type of loom.

The feeler arm on which the feeler tip is mounted, in accordance with the present invention, is supported to extend rearwardly towards the lay in a direction inclined to the longitudinal axis of the shuttle, but with permissive movement frontwardly under the frontward impulse of the surface within the shuttle on a detecting beat. This characteristic mounting for the feeler arm may be variously contrived, but in the present instance of the invention, the shipper stand 16 has pivoted thereto at 17 the feeler arm 18, so that the feeler arm 18 extends rearwardly in a direction inclined to the longitudinal axis of the shuttle or lay movement.

The details of the pivotal connection of the feeler arm 18 with the shipper stand 16 is best indicated in Fig. 4, which shows one good, practical means for effecting the desired mounting. As indicated in Fig. 4, the feeler arm 18 is pivotally supported by the stud 19 which has a shouldered portion 20 extending through the shipper stand 16. The smaller upper end 105 portion of the stud 19 is threaded as at 21

to receive the nut 22, between which and the feeler arm 18 is interposed a suitable washer 23.

Coiled about the lower portion of the stud 19 is the spring 24, one end 25 of which is connected to the feeler arm 18, and the other end of which rests or bears against the shipper stand 16 as at 26, the construction being such that the spring 24 normally tends to swing the feeler arm 18 into its rearward inclined position, as indicated in Fig. 1, and in dotted lines, Fig. 2. A stop is provided to limit the rearward movement of the feeler arm 18. In the present instance of the invention, the feeler arm 18 adjacent its pivotal support has a shoudered portion 27, Figs. 1, 2 and 3, which, when the feeler arm is in its normal feeling position as indicated in Fig. 1, and by dotted lines in Fig. 2, rests against a pin or stop 28, the construction being such that while the spring 24 normally acts to yieldingly hold the feeler arm 18 in its rearwardly inclined feeling position, as defined by the stop, it permits frontward movement of the feeler arm, on a detecting beat of the lay, as will more fully appear.

The details of the pivotal support of the feeler arm, and the yielding means for normally holding it in its rearwardly inclined position, constitutes a convenient mechanism for the purposes stated, but it is to be understood that the invention is not restricted thereto, but that any appropriate means may be employed which will serve to support the feeler arm in its rearwardly inclined position with permissive movement towards and from the front of the loom.

Mounted upon the feeler arm 18 for sliding movement thereon in a direction longitudinally of the shuttle, is the feeler tip 29. In the present instance of the invention, the feeler tip 29 has a sliding sleeve connection with the feeler arm. This is best shown in Fig. 5, wherein the feeler tip 29 has the sleeve portion 30 which embraces the feeler arm 18 and maintains the feeler arm and feeler tip in operative relation, the construction being such that the feeler tip 29 may be moved along the feeler arm in the general direction longitudinally of the shuttle or transversely of the loom.

The feeler tip is normally under the influence of a spring for holding it in its feeling position on the feeler arm. In the present instance, the feeler tip or preferably the sleeve 30 thereof, has rising therefrom the bearing or lug 31 through which extends one end of a rod 32. At either side of the bearing or lug 31 the rod 32 has threaded thereon the adjusting nuts 33, whereby the relation between the feeler tip and the rod 32 may be changed as circumstances dictate.

65 Rising from the feeler arm 18 is a lug 34

through which the rod 32 extends, and mounted upon the rod 32 with one end bearing against the face of the lug 34, and the other against one of the nuts 33, is the spring 35, the construction being such that the spring 35 will normally move the feeler tip towards the end of the feeler arm 18, but with permissive movement of the feeler tip along the feeler arm in a direction longitudinally of the shuttle. A suitable stop is employed for limiting the outward movement of the feeler tip 29 relative to the feeler arm, and in the present instance of the invention, such stop comprises a pin 36 secured to the feeler arm near its free end portion.

The rod 32 is provided with an eye 37, to which is connected a transmitter 38 for controlling the operative or inoperative relation between the rear end portion 7 of the actuator and its operating means or member 8. In the present instance of the invention, the loom frame or breast beam has rising therefrom the stand 39, to which is pivotally mounted at 40 a bell-crank lever, one arm 41 of which underlies the actuator 6, and the other arm portion of which is connected at 42 to the transmitter 38. The bracket or support 39 is provided with a stop 43 by means of which the bell-crank is limited in its movement upon its pivotal support 40 in one direction. The connection between the transmitter 38 and the bell-crank is preferably formed by a ball and socket joint, or other sufficiently loose connection to permit sufficient lost motion between the end of the transmitter 38 and its connection with the bell-crank to accommodate the swinging movement of the feeler arm 18, when the latter is moved frontwardly from its pivotal support on a detecting beat with filling substantially exhausted. The construction is such that the end 7 of the actuator 6, in the present instance of the invention, is normally in the path of movement of the operating member 8, and if it be not moved from such position on a detecting beat, filling replenishment will be effected, a condition which results when the filling is substantially exhausted from the shuttle on a detecting beat.

The rear end portion of the feeler tip 29 is provided with a series of teeth 44 which are preferably arranged in a curved series or circular arc, as indicated in Fig. 2, and which are of a character to sink into the filling when a working supply is present in the shuttle on a detecting beat.

When the lay is in its back position, the feeler arm 18 and the feeler tip 29 assume their feeling position, as indicated by full lines in Fig. 1, and dotted lines in Fig. 2, that is, the feeler arm 18 extends rearwardly in a direction inclined to the longitudinal axis of the shuttle, and the filling engaging teeth 44 of the feeler tip are positioned to enter

and engage the filling as the lay moves forwardly on a detecting beat.

When there is a working supply of filling in the shuttle on a detecting beat, the teeth 44 of the feeler tip 29 will engage and sink into the filling, and as the lay moves forwardly, the feeler arm 18 will be moved about its pivotal support 19 or swung from its dotted to its full line position, as indicated in Fig. 2. Since the filling 14 on the filling carrier is engaged by the teeth 44 of the feeler tip, the latter, that is, the teeth of the feeler tip, are prevented from moving along the surface of the filling, so that as the lay moves forwardly under such conditions, the feeler tip is moved along the feeler arm in a direction longitudinally of the shuttle, and against the action of the spring 35. Under such conditions the bell-crank pivoted 20 at 40 will be turned contra-clockwise, Fig. 1, and lift the end 7 of the actuator out of the path of the operating member. When, however, filling is substantially exhausted on a detecting beat, as indicated in Fig. 3, the teeth 44 of the feeler tip will no longer be able to hold the feeler tip from movement longitudinally along the filling carrier, and the parts will assume the position as indicated in Fig. 3, wherein it will be noted 30 that the feeler tip has not been substantially moved relatively to the feeler arm 18 from its initial position relative to the feeler arm as the lays beats up. Under these conditions the end of the actuator 6 will remain in the path of the operating member 8 as the latter moves forwardly, and filling replenishment will be effected.

From the construction described, the details of which form one good practical form 40 or embodiment of the invention, it will be noted that when a working supply of filling is present in the shuttle on a detecting beat, the feeler tip will be moved relative to the feeler arm in a direction longitudinally of the shuttle, and filling will not be replenished, but when filling is substantially exhausted on a detecting beat, the relation between the feeler arm and feeler tip remains unchanged on a detecting beat, and 50 filling replenishment is effected.

What is claimed is:—

1. In a feeler mechanism for looms, the combination of a feeler arm that is supported at the front of the loom and normally extends rearwardly in a direction inclined to the longitudinal axis of the shuttle, a feeler tip which is mounted for sliding movement along the feeler arm in a direction longitudinally of the shuttle by the forward pressure on the tip, and means for replenishing the filling connected to and controlled by the feeler tip.

2. In a feeler mechanism for looms, the combination of a feeler carrier which is pivotally mounted on the loom frame and has

a movement towards and from the front of the loom, a feeler having a filling engaging end and mounted on the feeler carrier for bodily sliding movement on the feeler carrier in a direction transversely of the loom by the forward pressure of a surface within the shuttle on a detecting beat, and means controlled by the feeler for effecting replenishment of filling.

3. In a feeler mechanism for looms, the combination of a feeler arm supported at the front of the loom and extending rearwardly in a direction inclined to the lay movement when the feeler arm is in rearward feeling position, a feeler tip having filling engaging teeth and which is mounted for sliding movement along the feeler arm in a direction longitudinally of the shuttle when a working supply of filling is present in the shuttle on a detecting beat, and means for causing replenishment of filling when the feeler tip fails to be moved along the feeler arm on a detecting beat.

4. In a feeler mechanism for looms, the combination of a feeler arm that is mounted at the front of the loom and extends rearwardly in a direction inclined to the longitudinal axis of the shuttle, a feeler tip mounted for sliding movement on the feeler arm in a direction longitudinally of the shuttle as the feeler arm moves forwardly on a detecting beat, a spring normally acting to yieldingly obstruct the movement of the tip along the arm, and means for replenishing filling when the tip fails to be moved along the feeler arm on a detecting beat.

5. In a feeler mechanism for looms, a feeler arm, means normally acting to yieldingly hold the feeler arm extending rearwardly in a direction inclined to the longitudinal axis of the shuttle, a feeler tip that is mounted for sliding movement along the feeler arm in a direction longitudinally of the shuttle and having teeth which engage the filling in the shuttle and effect such sliding movement of the feeler tip on a detecting beat until the filling is substantially exhausted, and means for effecting replenishment of filling when the feeler tip fails to be moved along the feeler arm on a detecting beat.

6. In a feeler mechanism for looms, the combination of a feeler arm that is pivotally supported, a feeler tip mounted on the feeler arm for bodily movement longitudinally along the arm in a direction transversely of the loom by the forward pressure upon it on a detecting beat, and means connected to the feeler tip for effecting replenishment of filling when that in the shuttle has become substantially exhausted.

7. In a feeler mechanism for looms, the combination of a feeler arm that is pivotally supported at the front of the loom and normally extends rearwardly towards the

- lay in a direction inclined to the lay movement, a feeler tip that is mounted to slide along the feeler arm in a direction longitudinally of the shuttle as the feeler arm swings about its pivot on a detecting beat, and means connected to the feeler tip for effecting replenishment of filling when the filling in the shuttle is substantially exhausted on a detecting beat.
- 10 8. In a feeler mechanism for looms, the combination of a feeler arm, a feeler tip which receives the forward pressure of a surface within the shuttle on each detecting beat and is mounted to slide on the feeler arm in a direction longitudinally of the shuttle by engagement with the filling until substantial exhaustion thereof, and means for effecting replenishment of filling when

on a detecting beat the feeler tip fails to slide on the feeler arm in a direction longitudinally of the shuttle.

9. In a feeler mechanism for looms, the combination of a feeler arm pivoted at a fixed point on the loom frame for pivotal movement toward and from the front of the loom, a feeler tip mounted on the feeler arm for sliding movement longitudinally along the arm by the filling on a detecting beat until substantial exhaustion thereof, a spring for sliding the feeler tip longitudinally along the arm after it has been displaced by the filling on a detecting beat, and means for replenishing the filling.

In testimony whereof, I have signed my name to this specification.

ISAAC SNOW.
